UNITED STATES PATENT OFFICE

169,033

COMBINATION STOOL AND STEPLADDER

Frederick L. Duer, Bellwood, Ill.

Application December 29, 1952, Serial No. 22,907

Term of patent 14 years

(Cl. D15—8)

To all whom it may concern:

Be it known that I, Frederick L. Duer, a citizen of the United States, residing at Bellwood, in the county of Cook and State of Illinois, have invented a new, original, and ornamental Design for a Combination Stool and Stepladder, of which the following is a specification, reference being had to the accompanying drawings, forming a part thereof.

In the drawings:

Figure 1 is a perspective view of a combination stool and stepladder, showing my new design.

Figure 2 is a side elevation of the same looking toward the wider side of the stool seat.

Figure 3 is a side elevation of said design, as shown in Figure 1, taken at substantially right angles to Figure 2.

Figure 4 is a perspective view of the combination stool and stepladder with the step portion thereof in its outwardly swung and operative position with relation to the stool.

Figure 5 is a side elevation of the same, i. e., the arrangement of the device as shown in Figure 4, and

Figure 6 is a top plan view of the combination stool and stepladder, particularly, with the parts thereof in the position illustrated in Figures 4 and 5.

I claim:

The ornamental design for a combination stool and stepladder, substantially as shown.

FREDERICK L. DUER.
